ABSTRACT: A guitar containing a battery-operated magnetic tape player carried in a compartment formed in the sound box portion of the instrument with the audio transducer of the apparatus being in acoustical relationship therewith. The pre-recorded tapes may contain speech or music for playback through the device.

FIG. 3

**MUSICAL INSTRUMENT CONTAINING INTEGRAL TAPE
PLAYER**

BACKGROUND OF THE INVENTION

The present invention is directed to a guitar, or other stringed musical instrument of the same general type, containing an integral tape player apparatus. The invention finds useful application as a toy item for the entertainment and amusement of children.

SUMMARY OF THE INVENTION

In the illustrative embodiment of the invention a battery-operated magnetic tape player mounted on the body of the instrument is provided for reproducing recorded speech or music, utilizing the sound box of the guitar as a natural mechanical amplifier for the generated sound.

The foregoing, and other objectives, features and advantages of the present invention will be more readily understood upon consideration of the following detailed description of the invention, taken in conjunction with the accompanying drawings.

BRIEF DESCRIPTION OF THE DRAWINGS

FIG. 1 is a front view of a guitar instrument, as modified by the present invention to carry a concealed weapon.

FIG. 2 is a front view of the same guitar instrument after the quick-release mechanism has been actuated and the weapon is delivered into a position ready for use.

FIG. 3 is a top plan view of the guitar instrument shown in the mode of **FIG. 2**.

DESCRIPTION OF THE PREFERRED EMBODIMENT

Referring initially to **FIGS. 1-3** of the drawings, there is shown a stringed musical instrument **10** in the form of a guitar of ordinary design outfitted with a concealed transistorized battery-operated magnetic tape player **25** of any suitable known design, carried in a compartment **26** in the upper portion of the guitar sound box **12**. A door **31** on the front face of the instrument provides access for changing reels, maintenance and repair of the tape player **25**. The operation of the tape player is controlled by an on-off volume control knob **29** mounted on the door **31**. Since the sound box **12** of the guitar forms a natural mechanical amplifier for sound waves, an acoustic transducer or speaker **27** of greatly reduced size can be utilized with the tape player **25**. In this version, with a tape player forming an integral part of the musical instrument **10**, it is contemplated that various pre-recorded tapes carrying, for example, teaching instructions on how to play a guitar, play-action dialogue, or music, would be used in conjunction with the instrument.

I claim:

1. The combination comprising a musical stringed instrument of the type having a sound box portion such as a guitar, a concealed compartment formed in the sound box portion of the instrument, and a battery-operated magnetic tape sound reproducing apparatus contained in said compartment, with the audio transducer of said apparatus being in acoustical relationship with said sound box portion, thereby providing natural mechanical amplification for the audio signals generated by said sound reproducing apparatus.
2. The combination as set forth in Claim 1 further including a tape for said sound reproducing apparatus having recorded thereon audio information in the form of teaching instructions for learning how to play said instrument.
